Specification of Letters Patent.

Patented Sept. 1, 1914.

Application filed September 21, 1905. Serial No. 279,481.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems, and has for its object the improvement of such systems by the use of what I term semi-automatic connections, that is those in which automatic switches are 15 used as auxiliaries to supplement the work of the operator. In the present case I employ these auxiliary mechanisms in two relations: The first set of mechanisms lie between the operator and the calling sub- 20 scriber, and the second set of mechanisms I interpose between the same operator and the wanted subscriber.

The progress of a connection is as follows: 25 The calling subscriber by simply removing his receiver from the hook selects an idle answering terminal somewhere on the board, and thereby gets immediate attention. The operator before whom the selected terminal and its associated signal are located, answers 30 the call and ascertains the number wanted. She then switches the calling line to a trunk leading to an automatic switch in whose banks the terminals of the wanted line are located; and by means of a sender associated 35 with her telephone set, she works the automatic switch to complete the connection. In other words, by uniformly distributing the load I economize the operators' time and work them at maximum efficiency all the 40 time, and I do away with the multiple in an ordinary switchboard, substituting trunks.

The appearance of the switchboard is very simple; each operator handling from three to five times as many lines as heretofore possible. With fifty answering-jacks, and from 45 25 to 50 pairs of plugs, the operator has an equal number of trunk-jacks. The percentage of selective switches to the number of lines is about ten, so that with fifty switches 50 the operator should average 500 lines. This, however, is probably a maximum, although with uniform distribution it is entirely within reason.

My invention is illustrated in the accompanying drawings wherein:

Figure 1 is a diagram showing a subscribers sub-station, a central station with a rotating selective device and also a connective circuit equipped with a sender. Fig. 2 is a similar diagram showing a trunk jack 60 terminating in a connector switch and a subscribers sub-station with central office equipment. Fig. 3 is a diagrammatic plan view showing the primary selector switch. Fig. 4 is a skeleton diagram showing line multiples 65 and the distribution of calls.

Referring to Fig. 1, I will first describe the selector switch and its operation and will then describe the circuit by which it is operated.

The selector I have shown comprises a constantly driven shaft X with a collar carrying the arm X' which in turn carries the contacts or wiper springs x⁸ and x⁹ which are constantly sweeping over the circularly arranged series of coöperating contacts. The wiper x⁸ sweeps over a continuous ring x⁷ while the wiper x⁹ sweeps over a series of contacts leading to different lines. The shaft in the present case is shown as being 70 driven by a belt L and a pulley L', but it will be understood that the driving means may be of any suitable description. The several selectors are all driven by preference from the same shaft so as to secure not only 75 economy of power and transmission, but perfect uniformity in speeds of the selector arms which may be swept over multiple contacts of the same line.

An individual selector mechanism such 80 as I have shown at X' comprises a sleeve or collar x¹⁰ mounted loosely on the shaft and held in position by the two collars x¹¹ and x¹² which are securely fastened to the shaft X. The movable collar x¹⁰ is fitted with a 85 projecting tubular arm preferably of copper or brass which carries the windings x¹³ and x¹⁴ upon it and the combination core or plunger x¹⁵ within it, the arm thus constituting in effect a solenoid with a plunger core. 90 The windings are held in place by the two spools x¹⁶ and x¹⁷. On the front spool end is fastened a case x¹⁸ which contains the coil spring x¹⁹ by which the plunger is normally kept retracted toward the shaft as 95 shown in the figure. The function of this plunger is two-fold. In the normal or idle condition of the parts it serves as a locking 100 detent or clutch to hold the arm fast on the shaft, its ends projecting at the same time 105

into an opening or socket in the shaft as indicated at x^{20} . When the arm is opposite the calling line terminal the plunger is thrown forward and its outer end enters 5 the jack ring x^{20} , the inner end at the same time leaving its socket in the shaft thus starting the arm and spreading the jack springs to form the necessary connections. The inner end of the plunger x^{18} is of soft 10 iron with a hard tip if necessary. Its outer end is of insulating material such as hard wood or fiber. The winding of the magnet is double consisting of an inner and outer layer like the primary and secondary of an 15 induction coil. One terminal of the outer winding is connected to the wiper x^8 , the other terminal of the coil being grounded. One terminal of the inner winding is connected to the wiper x^9 , the other terminal 20 being grounded. Of course these two windings of the solenoids may be placed on the tube or sleeve in any desired fashion. The only requirement is that either winding when energized shall be able to pull in the 25 core x^{15} .

The contacts or jack springs are built up in layers such as shown in the section, Fig. 1, and are arranged in a circle so that the wipers of the solenoid in rotating always 30 rest on some contact. All the lines in a certain position terminate in individual contacts and are multiplied in the banks of the switches of its position. There is a certain 35 percentage of these switches to each position in the exchange, usually about 10%, and instead of each line terminating in an answering jack it terminates in multiplied contacts of a group of these switches and these switches in turn pick out the line and 40 connect it to a trunk jack with a signal associated with it in front of an operator.

Having now described the operation of the selector switches or solenoids we will now take up the description of the circuits 45 by which they are controlled: In Fig. 1 the subscriber's station shown at A is equipped with apparatus usually found in common battery installations consisting of transmitter T, receiver R, hook H, ringers Q, condensers C. The lines from this station terminate in a line relay M to the normally closed contacts of the cut-off relay N. When the relay N is energized the line relay is 50 disconnected and the line wires 1 and 2 are connected to the multiple contacts in its group of switches through the extensions 5 and 6 respectively. Each line in addition to having multiple contacts in the banks of the selector switches also 55 has multiple contacts in the banks of connector switches for outgoing calls, from the central office to the substations. These connector switches terminate in multiple trunk jacks in front of the different operators. In a group of selector switches the

arms or solenoids are set radially around the shaft so that each line contact in each switch is swept over once during each revolution of its switch shaft. Since each line has a multiple in each of several switches, 70 the line will therefore be tested as many times during the period of one revolution as there are switches in its group. Suppose for illustration there are ten such switches and the shaft makes one revolution per second; 75 then since one line has ten multiple contacts, each of which is swept over once by its switch arm, there will be ten momentary contacts effected with the line during one second. By this arrangement the time consumed in answering a call by picking out 80 the calling line, is made of very short duration. This general arrangement is shown in skeleton form in Fig. 4. The line from subscriber's station "A" is carried to corresponding multiple contacts in the banks of 85 10 primary selectors marked from X^0 to $9X^0$, giving 10 answering multiples, and also to corresponding multiples in the banks of a number of selector switches indicated at $9X^0$ 90 Z^0 , $1Z^0$ and $2Z^0$. Another line 1^A is shown similarly connected, the subscriber's station for convenience being indicated upon the opposite side of the figure. It will be observed that the switch arms of the several 95 primary selector switches are arranged helically, or angularly spaced apart around the common driving shaft. Since each line is multiplied to vertical recurring or corresponding contacts in the several banks, it 100 follows that as all the arms sweep around in unison only one of them will touch a contact on the same line at any given instant, but in the course of a single revolution of the shaft, each of them will have passed over the contact of that line in its own bank, the 10 arms thus making 10 test contacts on the same line in a single revolution.

The front contact of the relay M is connected to the contact x' in the bank of the 110 switch X' and also to the multiple contacts in the other switches of the same group. The trunk wires 9 and 10 are connected to the bus contacts x^5 and x^6 respectively. These contacts are common to every pair 115 of line springs in the bank so that when the plunger of the solenoid is operated any line in the bank can be connected to the trunk wires 9 and 10. The contact x' is connected to the signal lamps through the contacts j' and j'' of the jack J and also to the normally opened contact p^{30} of the relay P^s . The relay P^s controls the solenoid magnet after the line relay has been disconnected. The trunk wires 9 and 10 terminate in the springs j and j' of the jack J. The cord or connective circuit consists of the answering plug P and calling plug P^s with their tips and sleeves respectively connected by the strand 20, condenser C, strand 120 125 130

22, strand 21, condenser C' and strand 23. Between the tip and sleeve of the answering plug the relays S and S' are connected with bridged battery furnishing talking current 5 for the calling subscriber. The third conductor p^2 of the plug P is connected to the normally open contact s^{10} of the relay S. This third conductor p^2 when placed in the jack J engages the thimble or ring j^3 , which 10 is connected to one terminal of the relay P^3 and also to the spring j^4 . This spring normally engages the spring j' connected to the sleeve side of the trunk. The sender or transmitting device is connected to the tip 15 and sleeve of the calling plug and is represented diagrammatically by the cams K and K'. When the cam K is operated ground impulses are sent over the tip or vertical side of the trunk operating the vertical relay in 20 the connector switch, Fig. 2, which in turn performs other functions. The cam K' when operated sends impulses over the sleeve or rotary side of the trunk operating the rotary relay S³ which in turn controls 25 the private relay side switches and tests, etc., in the connector switch. When both cams K and K' are operated simultaneously, impulses are sent in over the vertical and rotary sides of the trunk effecting the release of the switch as will be described later. 30

Referring now to Fig. 2 the connector switch here shown diagrammatically can be of any standard form that will respond to impulses over both sides of the line. For 35 illustration I have used the well known form of switch known as the Strowger type. In place of the ordinary back release relays which are connected to the called end of the trunk in the switch I have connected two 40 retardation coils I and I' with bridged battery furnishing talking current for the called subscriber, and instead of connecting the release magnet W' to the test wiper through the side switch z^6 I have connected 45 a sensitive relay W through this side switch to the tip or vertical wiper z' . This relay W controls the release magnet W'. I have dispensed with the ordinary third wiper which in the Strowger system is used for 50 testing, as I now test directly from the tip or vertical side of the line. The principal parts of this switch are the spindle Z carrying the wipers z' and z^2 which are insulated from one another. On the spindle Z there 55 is a ratchet with circular teeth engaged by the pawl controlled by the vertical magnet V, this magnet being operated by the vertical relay S² when the side switches z^3 , z^4 , z^5 , and z^6 are resting on the first contact. 60 These side switches are operated mechanically by the private relay P' after it first becomes energized and then deenergized. The energizing and deenergizing of this relay move the side switches one step. The 65 circuit of this relay is controlled by the ro-

tary relay S³ which responds to impulses over the rotary side of the line. On the spindle Z there is another ratchet with long teeth which when engaged by the pawl controlled by the rotary magnet V' causes the 70 spindle to rotate and the wipers z' and z^2 to pass over the contacts in the bank. The rotary magnet V' is controlled by the vertical relay S² after the side switches move from the first to the second position. The 75 ringing relay Y is also controlled by the relay S² after the side switches have moved the second time. This relay when energized disconnects the calling end of the trunk and places generator current on the called end thus supplying current for ringing the called 80 subscriber's bell.

The apparatus shown at the substation A' is identical with that of A, and the central office equipment for the lines from both 85 substations is the same, hence its description need not be repeated. The operation of my system is as follows: The subscriber at station A desiring to make a call removes his receiver from the hook which closes the circuit of the line relay M through the normally closed contacts on the cut-off relay N. The relay M becoming energized attracts 90 its armature and places battery on the multiple test contacts of the switches in which its line is multiplied. The circuit of one of the rotating solenoids in passing over this contact is closed by the following path: battery B, 12, m, m', 13, x' , x^6 , through one of the windings of the solenoid to ground. 95 This solenoid becoming energized the plunger x^{15} springs forward into the opening of the jack x^{10} and spreads the contacts x^5 and x^6 connecting a line to the trunk wires 9 and 10 respectively. As soon as this connection is completed the circuit of the relay N is closed by the following path: battery B, winding of the relay P³, 8, j^4 , j' , 10, x^6 , x^5 , 6, N, to ground. The relay N becoming 100 energized disconnects the line relay M and connects the line wires 1 and 2 to the trunk wires 9 and 10 through the extensions 5 and 6 respectively. The relay M being disconnected removes battery from the test contact x' but the solenoid is held energized 105 through the winding by the following path: battery B, 15, p^{10} , p^{20} , 11, x^7 , x^8 through the winding to ground. The relay P³ becomes energized at the same instant the relay M is disconnected thereby holding the 110 solenoid X' energized and at the same time closes the circuit of the lamp by the following path: B, 15, p^{10} , p^{20} , 11, 14, j^2 , j^3 , 12, s, to ground. The operator perceiving this 115 lamp glowing inserts the plug P into the jack J opening the contacts j^2 and j^3 extinguishing the lamp s. The contacts j' and j^4 are also disconnected removing the relay P³ from trunk wire 10. This relay now instead 120 of being held energized through the wind- 125

ing of the relay N has its circuit closed by the following path: ground s^{11} , s^{10} , p^2 , j' , 8, P^3 to battery B. Relays S and S' are held up by current through the subscriber's line as follows: battery B, relay S', 25, 21, p , j , 10, x^8 , x^3 , 6, 2, sub-station telephone, 1, 5, x^2 , x^5 , 9, j^3 , p , 20, 26, S and ground. There is an additional current flow from the battery through relay S' to ground 10 through the cut off relay N, which maintains the line connected to its extensions 5 and 6. The circuit of the relay N remains closed in series with the relay S' until the plug is removed. The operator throwing forward 15 her listening key asks for the number desired and instead of placing the calling plug in the multiple jack leading directly to the party desired, she places the calling plug P' into the trunk jack J' not busy and leading 20 to the connector switch containing the contacts of the line wanted. Having made this connection she operates the cam K a number of times responding to the tens numeral of the desired line. Referring now to Fig. 25 these impulses coming in over the vertical side of the trunk operate the relay S² which in turn closes the circuit of the vertical magnet V by the following path: ground, s^7 , s^6 , 43, p^4 , p^3 , 37, z^8 , 46, v , 48, 44, to battery B. 30 This magnet operating a number of times corresponding to the number of impulses causes the spindle Z to step up vertically bringing the wipers z' and z^2 opposite the row containing the contacts of the desired 35 line. After sending this set of impulses she operates the cam K' sending an impulse over the rotary side of the line operating the relay S³ which in turn closes the circuit of the private relay P¹⁰ by the following path: ground, s^7 , s^8 , P¹⁰, 42, to battery B. This relay in turn opens the contacts p^{23} and p^{24} disconnects the vertical magnet V preventing the spindle from making a vertical movement. After the impulses 45 come in and the relay P¹⁰ become deenergized the side switches make one step. In the switch z^3 the vertical magnet V is disconnected and the rotary magnet V' is connected in its place. In the switch z^8 the test 50 relay W is now in position for testing. The operator now manipulates the cam K sending impulses over the vertical side of the trunk corresponding to the unit numeral of the line desired operating the relay S², which in turn now closes the circuit of the 55 rotary magnet V' by the following path: ground, s^7 , s^6 , p^{24} , p^{23} , 37, z^8 , 45, V', 48, 44, to battery B. This magnet operating causes the spindle Z to rotate and the wipers z' 60 and z^2 to rest on the contacts of the desired line. She now operates the cam K' sending an impulse over the rotary side of the line operating the relay S³ which closes the circuit of the relay P' and connects the test 65 relay W to the tip side of the line by the

following path: battery B, W, 52, p^6 , p^5 , 36, z^6 , 53, z' , to z^7 .

If the called line was busy the contact z^7 would be grounded through the retardation coil I of some other switch and the relay W 70 would become energized closing the circuit of the release magnet and restoring the switch to its normal or idle position. Taking it for granted that the line called for is not busy, that is, no ground is found on the contact z^7 the relay W is not effected. After the rotary impulses come in the relay P¹⁰ becomes deenergized and the side switches move to the last position. In the switch z^8 the rotary relay V' is disconnected and the 75 ringing relay Y is connected in its place. In the switches z^4 and z^5 the trunk wires 29 and 30 respectively are connected to the trunk wires 49 and 50 through the normally closed contacts of the ringing relay Y thus 80 completing the connection between the calling and called subscriber. In the switch z^6 the test relay W is disconnected. The circuit of the relay N of the called subscriber is now closed by the following path: battery 85 B, 44, 35, 34, 30, y^3 , y^4 , 32, z^6 , 50, z^2 , z^8 , N, to ground. This relay becoming energized disconnects the line relay M and connects the line wires to the contacts z^7 and z^8 respectively. The operator now depresses the 90 cam K operating the relay S² which now in turn closes the circuit of the ringing relay Y in the same manner as it closed that of the vertical and rotary magnets. The relay Y becoming energized disconnects the calling 95 end of the trunk and sends current from the generator G to the wipers Z' and z^2 and from there to the station of the desired party. When the called party answers he 100 is supplied with talking current through the two retardation coils I and I'. 105

At the end of the conversation the calling subscriber upon hanging up opens his line circuit deenergizing the relay S which upon breaking the contacts s^{10} , s^{11} , opens the circuit of the relay P³. The relay P³ now opens the contacts p^{10} and p^{20} disconnecting battery from the winding of the solenoid, the plunger of which under the influence of the coiled spring returns to its normal position, and the switch X' again begins to rotate. The operator noticing the lamp s^0 glowing after the calling party is disconnected withdraws the plug P from the jack J and depresses the cams K and K' simultaneously operating both the vertical and rotary relays S² and S³ at the same time. These relays operating in this manner close the circuit of the release relay W by the following path: ground, s^5 , s^9 , 52, W, 115 to battery B. This relay now in turn attracts its armature, closes the circuit of the release magnet W' which restores the switch to its normal or idle position. 120

Instead of the operator pressing the cams 120

K and K' at the end of the conversation to release the switch it can be done automatically. I have shown it in the manner illustrated for simplicity.

5. Having thus described my invention, what I claim and desire to secure by Letters Patent is:

1. In a telephone exchange system, a plurality of subscribers' lines, a plurality of answering terminals less than the total number of subscribers' lines, connecting or calling terminals for the subscribers' lines, an operator's connective circuit adapted to connect an answering with a calling terminal, 15 automatic switching means responsive to current in a calling line to connect the same with an answering terminal, a calling signal operative upon making said connection but cut-out when the call is answered, together with a supervisory signal rendered operative when the call is answered, and automatic connective switching means intermediate the calling terminals and the subscribers' lines.

25 2. In a telephone exchange system, a plurality of subscribers' lines, a plurality of answering terminals less than the total number of subscribers' lines, connecting or calling terminals for the subscribers' lines, an operator's connective circuit adapted to connect an answering with a calling terminal, 30 automatic switching means responsive to current in a calling line to connect the same with an answering terminal, a calling signal placed under control of the calling subscriber through said switching means, a supervisory signal placed under control of said subscriber in answering a call, and automatic connective means interpolated between calling terminals and subscribers' 35 lines and arranged to be directly actuated to connect the calling terminals with the subscribers' lines.

40 3. In a telephone exchange system, a plurality of subscribers' lines, a plurality of answering-jacks less in number than the number of lines, a primary selector switch associated with each answering jack and containing line-terminals, automatic controlling means for said switch responsive to a call over any of the lines having terminals in the switch, and operator's connective apparatus adapted to coöperate with said answering jacks, to complete the connection of 45 the line calling with a line wanted, and switching means transferring the control of said selector switch to the operator upon connection of the operator's circuit with said answering jacks, substantially as described.

50 4. In a telephone exchange system, a plurality of subscribers' lines, a plurality of answering jacks less in number than the number of lines, a plurality of connecting jacks having connection with the lines, au-

55 tomatic primary selector switches for connecting the lines to the answering jacks, operators' means to connect an answering jack with a connecting jack, means to actuate said switches controlled by a line in calling, and retaining means independent of the said actuating means and holding the switch in actuated positions until connection is made with an answering jack.

60 5. In a telephone exchange system, a plurality of subscribers' lines, a plurality of answering-jacks, a selector switch associated with each answering-jack and containing line-terminals, a controlling magnet for said switch, means to drive the switch, means controlled by a line in calling to determine the actuation of said magnet and the control of the switch to connect the calling line with an answering-jack, and retaining means for the said switch independent of the line, substantially as described.

65 6. In a telephone exchange system, a plurality of subscribers' lines terminating at a central office, answering terminals therefor less in number than the number of subscribers' lines, manual connective apparatus adapted to connect with said answering terminals and including an operator's set and a supervisory signal, and means controllable by a calling subscriber and normally disassociated from manual apparatus and operator's set to automatically connect the subscribers' lines to said answering terminals, together with automatic means controlled through the said manual apparatus to effect 70 connection between said answering terminals and called lines.

7. In a telephone exchange system, a plurality of subscriber's lines terminating at a central office, answing terminals therefor less in number than the number of subscribers' lines, manual connective apparatus adapted to connect with said answering terminals and including an operator's set and a supervisory signal, and means controllable by a 75 calling subscriber and normally disassociated from manual apparatus, lines, and operator's sets to automatically connect the subscribers' lines to said answering terminals, together with means controlled by the operator through said manual apparatus to cause the answering terminals to be automatically connected to wanted line terminals, substantially as described.

8. In a telephone exchange system, a plurality of line-circuits and connective means comprising means to distribute incoming calls by connecting the calling lines to various answering terminals, automatic devices for connecting with wanted lines, means to 80 switch said answering terminals manually to automatic devices and means whereby said automatic devices will complete the connections to the wanted lines, each of said line circuits having terminals multiplied in said 85 90 95 100 105 110 115 120 125 130

distributing means and said automatic connective devices, substantially as described.

9. In a telephone exchange system, line-circuits and connective apparatus therefor used in sets with interchangeable units, the first unit or link of each set having an automatic selector switch for one terminal to pick up lines calling, and an individual spring jack for the other terminal, the second unit or link composed of an operator's plugs and cord-conductors, and the third unit or link composed of a trunk-line terminating at one end in a jack associated with the operator's plugs and cords, and at the other end in an automatic connector switch containing line-terminals multiplied from the selector switches of the first link, substantially as described.

10. In a telephone exchange system, a plurality of line-circuits, a primary selector switch, an individual terminal or answering-jack, therefor, an operator's cord-circuit having a sending mechanism associated therewith, a trunk jack, a trunk line leading therefrom and an automatic connector switch containing line-terminals, said primary selector being automatically operated by the subscriber in calling to connect the calling line with the answering jack, and said automatic connector switch being controlled by the operator through her sender to complete the desired connection and said lines having multiplied terminals in each of said selector and connector switches, substantially as described.

11. In a telephone exchange system, line circuits 1-2, relays M and N associated with each line, an automatic selector switch containing terminals, α' , α^2 , α^3 , α^5 and α^6 , a controlling magnet and driving means for said switch, a spring-jack J, with an associated signal s, and a controlling relay P, an oper-

ator's cord-circuit having terminal plugs P, P', bridged relays S, S', a supervisory signal s⁰, and a sender with switching means, 45 K, K', together with a trunk jack J' and an automatic connector switch Z connected thereto, containing line-terminals, and adapted to be controlled by the operator's sender, substantially as described. 50

12. In a telephone exchange system, a plurality of subscribers' lines, connection links between said lines, one of said links consisting of a selector switch adapted to make connection with a calling line, a second link 55 comprising an operator's manual cord circuit and adapted to be connected with the automatic switch through a spring jack associated with the latter and a third link comprising a trunk circuit having an automatic 60 selector switch adapted to be controlled by the operator to select and connect with a wanted line, said lines having multiplied terminals in each of said switches.

13. In a telephone exchange system, subscribers' lines, a central office provided with an automatic selector switch for selecting and connecting with a calling line, an automatic connector switch for connecting with a wanted line, said lines having answering 70 and connecting multiples in the switches respectively, and an operator's cord circuit adapted to connect said automatic selector and connector switches through spring jacks associated with the respective switches, and 75 means included in said cord circuit to control said automatic connector switch to effect connection with the wanted line.

In testimony whereof I have affixed my signature in presence of two witnesses.

EDWARD E. CLEMENT.
